UNITED STATES PATENT OFFICE.

MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

LOCK-STITCH SEWING MACHINE.

Application filed March 26, 1924. Serial No. 701,894.

This invention relates to high-speed lock-stitch sewing machines, more particularly of the type represented in my copending application Serial No. 651,800, filed July 16, 1923, 5 wherein a rotary hook is provided for carrying the needle-loop around a stationary bobbin-thread case. With stitch-forming mechanism of this type, it is necessary to provide means for restraining the thread-case 10 against rotation while permitting free passage of the needle-loops about the thread-case. The rotation restraining means may, for example, comprise a tongue mounted on the frame of the machine and loosely entering 15 a notch in the thread-case. As the needle-loop is being drawn up, it is necessary for such loop to ultimately pass through the space between said tongue and the walls of said notch, and much difficulty has in the 20 past been experienced in securing free and easy passage of such loop through such space at high speeds. The difficulty spoken of is increased by an increase in the size of the under thread-mass which necessitates the use 25 of a larger and consequently heavier thread-case, the inertia of which is a prominent factor to be reckoned with.

When sewing with certain threads, for example, wiry threads, the needle-loops have 30 a pronounced tendency to twist and kink, particularly at the times when such loops are being drawn up after escaping from the thread-case. This twisting or kinking often 35 prevents the complete taking up of the needle-loops and such loops make an unsightly showing on the under face of the work. If the usual sewing tension is increased in an effort to accomplish the complete drawing up of such loops, thread 40 breakage is likely to result.

Further, in machines wherein a stationary bobbin-case is supported within the field of action of the looptaker, the passage of the needle-thread loops about the bobbin-case 45 necessitates the cyclical lifting of the bobbin-case from its support. Where, as in a machine such as disclosed in my said copending application, a large bobbin-case is used, and mechanical means are employed 50 for lifting the bobbin-case, there is a tendency for such case to harshly strike the raceway in the hook, causing friction and noise.

I have discovered that by providing means 55 close to the under face of the throat-plate

for yieldingly nipping and preventing twisting of the needle-thread loop until it is reduced to the smallest possible size, finally allowing the loop to escape with a snap, that is, while under a light strain or tension, like 60 a stretched rubber band, such loop will when released fly up to the work so quickly that it has no time to twist or kink. Whatever the action may be, experiment has demonstrated that a machine equipped with this 65 spring will satisfactorily sew at high speeds using wiry threads which cannot be as satisfactorily handled without it under equivalent conditions of speed and under-thread capacity. I have also discovered that by opposing such spring to the bobbin-case lifting means, overthrow of the bobbin-case is prevented and a quieter and more nearly frictionless operation is secured. 70

In the accompanying drawings, Fig. 1 75 is an elevation of the stitch-forming instrumentality of a rotary hook sewing machine embodying the invention. Fig. 2 is a plan view of the under thread mechanism. Figs. 3, 4 and 5 are views similar to Fig. 1 at successively later stages of a stitch-forming cycle, showing the passage of a needle-thread loop through the rotation restraining notch and the control and tensioning of such loop, and Fig. 6 is a fragmentary front end elevation of the machine showing the parts 80 above the throat-plate. 85

For the purposes of the present disclosure the invention is described as embodied in a rotary hook sewing machine having the constructive features represented in my said copending application. Such a machine is 90 constructed with a reciprocating needle 1 and a rotary hook 2 making three revolutions to one reciprocation of the needle. 95 The machine also has the usual throat-plate 3, presser-foot 4 and feed-dog 5 which latter is carried by the feed-bar 6 and is given feed-and-return movements by the shaft 7 and rising-and-falling movements by the shaft 8. 100

The needle 1 is carried by the needle-bar *a* actuated by the crank *b* on the shaft *c* through the usual link connection *d*. The needle-thread passes, as usual, through the upper thread-tension *e*, under the light check 105 spring *f*, through the take-up *g* and thence to the needle.

Supported within the field of action of the rotary hook 2 on the hanger-disk 9 is the thread-case 10 having ledges 11 resting upon 110

the hanger-disk. The thread-case is formed with the rotation restraining notch 12, Fig. 2, which is loosely entered by the tongue 13 carried by the hanger-disk 9 said tongue including a movable jaw 14 which may be expanded by manipulation of the latch 15, Fig. 1, to grip the adjacent wall of the notch 12 for removal of the bobbin-case. When in operative position the tongue 13, including the jaw 14, does not fill the space between the forward and rearward walls of the notch 12 and it is through this space that the needle-loop must be drawn in its passage up to the work.

15 The present machine also preferably employs a mechanical lifter 16 which is actuated by the feed-lifting rock-shaft 8 and engages the thread-case 10 and lifts the ledges 11 clear of the hanger-disk 9, Fig. 3, as the needle-loop is being drawn up, so that the said loop is not obliged to stand the strain of bodily lifting the thread-case.

Secured to the hanger-disk 9 by screws 17, Fig. 1, are the leaf-spring 18 and its guard 19. The upper free end of the spring 18 bears lightly against the rearward wall of the loop-detaining horn 20 at the extreme upper end of the latter and normally holds open the mouth 21 of the passageway between the tongue 13 and the forward wall of the notch 12; said mouth being at that side of the tongue 13 first passed by the rotary hook and thus in position to readily receive the supply limb of the needle-loop being drawn up. The spring 18 also overhangs one of the ledges 11, as shown in Fig. 2, and cushions the upward movement of the bobbin-case under the influence of the lifter 16, thus reducing friction and noise by preventing the bobbin-case from harshly striking the raceway in the hook 2.

The passage of the needle-loop about the bobbin-case is accomplished in substantially the same manner as described in my said co-pending application. In the present instance, however, the work-limb of the needle-loop is detained by the spring 18 while the supply limb is drawn first into the open mouth 21 of the passageway between the tongue 13 and the walls of the notch 12. Finally, after having been drawn through said passageway, the loop is drawn between the tension-spring 18 and the horn 20 as shown in Fig. 5, and is frictionally held under control and prevented from twisting until it is reduced to the smallest possible size. The needle-thread is at this time under a light strain or tension, caused by the tensioning action of the nipper spring 18, so that when the needle-loop escapes from such spring it escapes with a snap and will be

65 jerked up to the work before it has time to twist or kink. The action of the check-spring 18, or the natural elasticity of the thread, or both, contribute to the quick take up of the needle-loop when released by the spring 18.

Having thus set forth the nature of the invention, what I claim herein is—

1. In a sewing machine, a reciprocating needle, a loop-taker, a bobbin-case, a rotation restraining device associated with said bobbin-case, a take-up, and a yielding thread-nipper through which the needle loop is drawn by the take-up after such loop has passed between the bobbin-case and the rotation restraining device. 70

2. In a sewing machine, a reciprocating needle, a loop-taker, a take-up, a bobbin-case having a loop-detaining horn, and a needle-loop tensioning spring coacting with said horn to tension the needle-loop immediately prior to releasing the same. 80

3. In a sewing machine, a reciprocating needle, a loop-taker, a throat-plate, a bobbin-case, means for restraining the bobbin-case against rotation, and yielding means disposed below the throat-plate and adapted to nip the needle-loop after it has passed the rotation restraining means. 85

4. In a sewing machine, a reciprocating needle, a rotary hook, a bobbin-case, a bobbin-case support, a bobbin-case lifter, and a buffer spring adapted to cushion the movement of the bobbin-case initiated by said lifter. 90

5. In a sewing machine, a reciprocating needle, a rotary hook, a bobbin-case, a rotation restraining device, said case and device having loosely interengaging portions affording therebetween a passageway for the needle-loop, and a spring mounted independently of and bearing upon said bobbin-case and yieldingly urging the latter at all times in a direction to open the entrance to such passageway. 100

6. In a sewing machine, a reciprocating needle, a rotary hook, a bobbin-case, a rotation restraining device, said case and device having loosely interengaging portions affording therebetween a passageway for the needle-loop, and a spring mounted independently of and bearing upon said bobbin-case and yieldingly urging the latter at all times in a direction to open an entrance to such passageway at the side of said interengaging portions first passed by the rotary hook. 110

In testimony whereof I have signed my name to this specification.

MARTIN HEMLEB.
